UNITED STATES PATENT OFFICE.

ISIDOR LEVY, OF BROOKLYN, NEW YORK.

RECEPTACLE.

Application filed January 19, 1922. Serial No. 530,418.

To all whom it may concern:

Be it known that I, ISIDOR LEVY, a citizen of the United States, and a resident of the city of New York, borough of Brooklyn, in the county of Kings and State of New York, have invented a new and Improved Receptacle, of which the following is a full, clear, and exact description.

The present invention relates to new and useful improvements in receptacles, and it pertains more particularly to a receptacle especially adapted for containing cakes and similar perishable foods.

It is one of the objects of the invention to provide a device of this character in which a sliding door controls access to the compartment in which the articles are adapted to be placed.

It is a further object of the invention to construct a sliding door so that the same will be readily operable to open and close the aperture through which the interior of the receptacle is reached.

It is a still further object of the invention to construct a device of this character in such a manner that the device is simple of construction, easy of operation, and can be manufactured and sold at a reasonably low price.

With the above and other objects in view, reference is had to the accompanying drawings, in which—

Figure 1 is a view in elevation of a receptacle constructed in accordance with the present invention;

Fig. 2 is a vertical sectional view thereof;

Fig. 3 is a horizontal sectional view taken on the line 3—3 of Fig. 1.

Referring more particularly to the drawings, the device comprises a top member 5 and a bottom member 6, and each of these members is formed with a flange 7, the edge of which terminates in a roll or similar bead 8. The reference character 9 designates the body of the receptacle, and said body is secured to the top member 5 and bottom member 6, by means of solder or the like 10.

The receptacle is adapted to be circular in cross-sectional form, and the outer diameter of the receptacle body 9 is of less dimension than the inner diameter of the flanges 7 of the top and bottom 5 and 6.

By this construction it is apparent that a space 11 is provided between the flanges 7 and 5 of the top and bottom 5 and 6, respectively.

The body portion 9 is formed with an opening 12 by cutting away a portion thereof, and the edges of the body portion 9 which define this opening, are rolled back to form a bead 13. This opening 12 is adapted to be closed by means of a sliding door 15, and said sliding door 15 is curved concentrically with the curvature of the body portion 9 and the curvature of the top and bottom 5 and 6, respectively. Adjacent each end the door is provided on its outer face with a flange 16, and said flanges 16 are adapted to receive their respective beads 17 formed on the top 5 and bottom 6. By this construction it is apparent that the lower flange 16 forms a support for the door and the upper bead 17 forms a guide for the door in its operation.

The interior of the receptacle may be provided with a plurality of shelves 20 and the sliding door 15 may likewise be provided with an operating handle 21 of any desired type.

From the foregoing it is apparent that the present invention provides a new and novel form of cake box or similar receptacle, and, at the same time, a structure which is simple in construction, cheap in cost of manufacture, as well as effective for the purpose intended, is had.

What is claimed is:

A receptacle comprising a cylindrical body portion having a portion cut away to provide access to the interior thereof, a flanged plate secured to each end of the body portion, said flanged plates being of larger diameter than the diameter of the cylindrical body portion and each plate having a flange extending around its respective end of the cylindrical body portion in spaced relation thereto, a sliding plate conforming to the cylindrical shape of the body portion and adapted to close the access opening thereof, said plate having its edges received in the space between the flanges of the end plates and the cylindrical body portion, and a flange secured to each edge of said closure plate and overlying the flange of its respective flanged plate.

ISIDOR LEVY.
